JEAN GEISSLINGER, OF FOREST HILLS, NEW YORK, ASSIGNOR TO EMILE BECK, OF GENEVA, SWITZERLAND

CLOCKWORKS WITH ELECTRIC WINDING DEVICE

Application filed September 26, 1928, Serial No. 303,430, and in Switzerland October 5, 1927.

This invention relates to clock-works provided with electric winding devices of the kind wherein a ratchet wheel cooperates with a driving pawl and a locking pawl, the driving pawl being operated by the armature of an electro-magnet.

The object of the invention is to provide a device of the above indicated character in which each one of the two pawls forms a movable contact-piece of the circuit interrupter of the electro-magnet.

The accompanying drawings illustrate by way of example a practical embodiment of the invention.

15 Fig. 1 is a plan view and Fig. 2 an elevation of the device. Figs. 3 and 4 show some details drawn to a larger scale.

1 is the pillar-plate supporting the clock-movement, which is not illustrated, and the 20 electro-magnet 2 acting upon its armature 3 which is provided with the antagonistic spring 4. To the armature is hinged the driving pawl 5 operating the ratchet wheel 6 which engages the clock-movement and is 25 held against reverse rotating by the locking pawl 7.

One of the poles of the source of current is connected to the pillar plate in 8, the other pole leads to the insulated terminal 9 mounted 30 on the carcass of the electro-magnet; from there the current flows through the coil of the electro-magnet, then through the insulated wire 10 to the spring blade 11 mounted on the locking pawl 7 with the intermediary 35 of an insulating layer 12.

The Figure 4 shows the pawl 5 almost at the end of a driving stroke. The locking pawl 7 is on top of one of the teeth of the ratchet wheel 6; the moment when the pawl 40 5 completes its driving stroke, the pawl 7 falls into the space between two adjacent teeth (see Fig. 3) and contact is made between the two pawls 5 and 7. The circuit of the electro-magnet is closed and the armature 3 is attracted until the pawl 5 has been pulled back 45 over one tooth of the ratchet wheel; then the contact is broken between the two pawls the armature is pulled off by the spring 4 whereby the pawl 5 turns the ratchet wheel for 50 one tooth.

As the pawl 7 falls abruptly into the space between two teeth the circuit is closed very suddenly; when the pawl 5 is pulled backwards owing to the action of the electro-magnet upon its armature, it stays in contact with the spring blade 11 during the greater part of its stroke while at the same time it is being displaced with regard to this contact; therefore a friction is brought about between the two contacts maintaining the 55 surfaces in good condition and preventing the formation of an oxide layer.

I claim:

An electric clock comprising a ratchet wheel, an electric circuit, an electromagnet 65 included in said circuit and provided with an armature, a driving pawl for said ratchet wheel, said driving pawl being hingedly secured to the armature and included in said circuit, an insulatedly mounted locking pawl, 70 and a contact spring insulatedly mounted on the locking pawl, said contact spring and said driving pawl forming the circuit interrupter for the electromagnet, and the contact spring being adapted to maintain contact with the driving pawl by sliding over the pawl throughout the entire attractive stroke of the armature.

In testimony whereof I affix my signature.
